UNITED STATES PATENT OFFICE.

ERAZM GLOWACKI, OF MIELNICA, AUSTRIA-HUNGARY.

AIR-MOTOR.

SPECIFICATION forming part of Letters Patent No. 705,834, dated July 29, 1902.

Application filed August 2, 1901. Serial No. 70,698. (No model.)

To all whom it may concern:

Be it known that I, ERAZM GLOWACKI, a subject of the Emperor of Austria-Hungary, residing at Mielnica, Galicia, in the Empire 5 of Austria-Hungary, have invented certain new and useful Improvements in Air-Motors, of which the following is a specification.

The object of the present invention is a construction of motor for utilizing the force of 10 the wind in which the force of the wind, which is to act on a certain resisting surface, can be either fully or partially utilized.

In the drawings, Figure 1 is a side elevation of the wind motor and apparatus. Fig. 15 2 is a plan of the disk provided with foldable cells. Figs. 3 and 4 are detail views of a portion of one of the cells on the disk. Fig. 5 is a top view of a drum, showing the foldable cells open; and Fig. 6 is a view of the same, 20 showing the cells closed. Fig. 7 is a diagrammatic view showing the arrangement of adjusting-plates.

On a common axle *a* are placed two drums 25 provided with recesses like those of a turbine wheel and at the top a circular plate with semifunnel-shaped cells. This axle has a bearing on a wooden staging *b* and is set in rotation by means of the pressure of the wind on the cells. The whole apparatus is inclosed 30 in another wooden framework *c*, on which four independently-movable adjusting-plates *d*, Fig. 7, are pivoted on hinges *f*. The object of these plates is, by means of their suitable adjustment, to protect the half of the 35 side turned toward the wind, whereby the other half of the drum and the upper cells are exposed to the force thereof.

Each drum is constructed as follows: On a 40 wooden cross *g*, Fig. 6, are arranged a straight bar *h* and another bar *k*, pivoted on the axle *a*, segmental at the sides and provided with curved slits *i*. On the end of this latter bar is a folding heel-piece *l*, pivoted, as by a hinge, to move at substantially right angles to the 45 bar *k* and formed in the shape of an *L*, in the eye of which heel-piece engages a pin *m*, attached to the straight bar *h*, when the two bars are pushed on one another and the heel-piece is folded up. On the rim *n*, Figs. 5 and 50 6, of the drum, both at the top and bottom, are pivotally (*o*) arranged steel ribs *p*, inclosed in stretched canvas, so as to form in this

manner cells. A cord *r* runs in rings around these cells, by means of which they can be drawn together when the bars *k* and *h* are 55 moved apart, whereby the pins *s*, engaging in the slots *i* of the one bar and attached to two steel ribs, effects the folding up of the cells. The cord *r* may either be of elastic material or of such length as to allow of the 60 opening of the cells after having been closed, in which latter case one end of the cord would be fixed to a cell, but the other end would be removably attached to a cell, as by tying. The semifunnel-shaped cells, Figs. 1 and 2, 65 at the top are formed by curved upright steel ribs *t* and by the canvas stretched on the ribs and on the disk *u*. The steel ribs *t* are pivoted on their straight sides to the disk *u*. The cells on both halves of the disk *u* are laterally connected with each other by means of a cord *v*, so that when one cell is drawn up 70 the others come with it. This is effected by means of another cord *x*, fixed in the center to the first cell and running on rollers supported on posts to a spring-catch *w*, Figs. 3 and 4. If the cells are to be folded up, it is only necessary to release the catch *w* from a pin *y*, Fig. 3, in which it is fixed. In order to effect this during the revolution of the disk 80 *u*, an arm of a pivoted lever *z* on the wooden staging *b* has to be pulled up by means of the cord *v*. The catch *w* is obliged to strike on this arm and is thereby raised and released. The release of the heel-piece *l* on both drums 85 is effected in exactly the same manner by means of the cords *v*² and *v*³, Fig. 1.

Each adjusting-plate *d* is provided at the top with a flap *d'*, and the axle *a* is provided with an ordinary strap-brake *b'*. 90

The motor operates as follows: Assuming that the wind is blowing from the front, Figs. 1 and 7, then one-half of the cells, with the adjusting-plate *d* and raised flap *d'*, is to be protected from the wind which is conducted 95 to the other cells. Thereby the axle *a* is revolved or any apparatus—such as a pump, mill, or the like—set working. If the force of the wind is only to be partially utilized, the upper cells or those on one or other of the 100 drums can be put out of operation without stopping the working entirely. Moreover, if necessary, the strap-brake *b'* can be used for moderating or entirely stopping the working.

Having thus described my invention, what I claim as new, and desire to secure by Letters Patent, is—

1. In a wind-motor, the combination of a staging, a motor provided with cells and adjusting-plates pivoted to the staging for protecting portions of the motor from the wind, said plates being provided with adjustable flaps, substantially as described.
2. A drum for a wind-motor consisting of an axle, a frame thereon provided with a bar *h* extending therefrom, another bar *k* pivoted on the axle, means for connecting the bars to each other, ribs *p* pivotally connected to the frame, and supporting material to form cells, a cord *r* connecting the cells to each other, and means on the bar *k* coöperating with the ribs to cause two of the ribs to follow the motion of the bar when the bars are moved apart and toward each other, substantially as described.
3. A drum for a wind-motor consisting of an axle, a frame thereon provided with a bar *h* extending therefrom, another bar *k* pivoted on the axle and having segmental portions provided with slots *i*, means for connecting the bars *k* and *h* to each other, ribs *p* pivotally connected to the frame, and supporting material to form cells, pins *s* on two of the ribs, engaging the slots *i*, and means connecting the cells to each other in such manner that when the bars *k* and *h* are moved apart to cause the pins *s* to move in the slots *i*, the cells will be folded up, substantially as described.
4. In a wind-motor, the combination with a staging, of an axle having bearings thereon, and a drum consisting of a frame *g* on the axle provided with a bar *h* and another bar *k* pivoted on the axle, said bar *k* being segmental at the sides and having curved slots *i*, a folding heel-piece *l* on the end of the bar *k* having an eye adapted to engage a pin *m* attached to the bar *h*, a rim *n* on the frame *g*, ribs *p* pivoted to said rim at top and bottom and inclosed in stretched cloth to form cells, pins *s* on two ribs engaging the slots *i* in the bar *k* and a cord *r* running around the cells in rings to draw them together when the bars *k* and *h* are moved apart to cause the pins *s* to move in the slots *i*, substantially as described.
5. In a wind-motor, the combination with a staging, of an axle having bearings thereon and a disk *u* on the axle provided with cells formed by upright ribs *t* with cloth stretched thereon and on the disk *u*, cords *v* connecting the cells on each half of the disk and another cord *x* fastened to one disk and passing over rollers to a catch for raising and lowering the cells, substantially as described.
6. In a wind-motor, the combination with a staging, of an axle having bearings thereon and a disk *u* on the axle provided with funnel-shaped cells formed by curved upright steel ribs *t* and cloth stretched on said ribs and on the disk *u*, cords *v* laterally connect-

ing the cells on both halves of the disk arranged to raise the disks when one of them is raised and another cord *x* fixed to one cell and passing over rollers to a spring-catch *w* held by a pin *y*, substantially as described.

7. In a wind-motor, the combination with a staging, of an axle having bearings thereon, and a drum consisting of a frame *g* on the axle provided with a bar *h* and another bar *k* pivoted on the axle, said bar *k* being segmental at the sides and having curved slots *i*, a folding heel-piece *l* on the end of the bar *k* having an eye adapted to engage a pin *m* attached to the bar *h*, a rim *n* on the frame *g*, ribs *p* pivoted to said rim at top and bottom and inclosed in stretched cloth to form cells, pins *s* on two ribs engaging the slots *i* in the bar *k*, a cord *r* running around the cells in rings to draw them together when the bars *k* and *h* are moved apart to cause the pins *s* to move in the slots *i*, and means for releasing said heel-piece while the drum is rotating, substantially as described.

8. In a wind-motor, the combination with a staging, of an axle having bearings thereon and a disk *u* on the axle provided with cells formed by upright ribs *t* with cloth stretched thereon and on the disk *u*, cords *v* connecting the cells on each half of the disk, another cord *x* fastened to one disk and passing over rollers to a catch for raising and lowering the cells, and means for releasing said catch while the disk is rotating, substantially as described.

9. In a wind-motor, the combination with a staging, of an axle having bearings thereon and a disk *u* on the axle provided with funnel-shaped cells formed by curved upright steel ribs *t* and cloth stretched on said ribs and on the disk *u*, cords *v* laterally connecting the cells on both halves of the disk arranged to raise the disks when one of them is raised, another cord *x* fixed to one cell and passing over rollers to a spring-catch *w* held by a pin *y*, and means for releasing said catch *w* while the disk is rotating, substantially as described.

10. In a wind-motor, the combination with a staging, of a vertical axle having bearings thereon, drums on the axle provided with cells, a disk on the axle provided with upright cells and adjusting-plates pivoted on the frame for protecting portions of the drums from the wind, said plates being provided with adjustable flaps, substantially as described.

11. In a wind-motor, the combination with a staging, of a vertical axle having bearings thereon, drums on the axle provided with foldable cells, a disk on the axle provided with vertical foldable cells and adjusting-plates pivoted on the frame for protecting portions of the drums from the wind, substantially as described.

12. In a wind-motor, the combination with a staging, of a vertical axle having bearings thereon, drums on the axle provided with

foldable cells, a disk on the axle provided with vertical foldable cells, and adjusting-plates pivoted on the frame for protecting portions of the drums from the wind, said plates being provided with hinged flaps for protecting portions of the disks and their cells from the wind, substantially as described.

13. In a wind-motor, the combination with a staging, of a vertical axle having bearings thereon, drums on the axle provided with foldable cells and means for maintaining said cells in an unfolded position, a disk on the

axle above the drums provided with vertical foldable cells, and means for maintaining said cells unfolded, and means for folding either 15 or both sets of cells while the drums and disks are rotating, substantially as described.

In testimony whereof I have signed my name to this specification in the presence of two subscribing witnesses.
